UNITED STATES PATENT OFFICE

170,727

CORNER SINK

Jacques Stanitz, Warren, Ohio, assignor to Mullins Manufacturing Corporation, Salem, Ohio, a corporation of New York

Application June 30, 1953, Serial No. 25,741

Term of patent 14 years

(Cl. D4—2)

To all whom it may concern:

Be it known that I, Jacques Stanitz, a citizen of the United States, residing at Warren, in the county of Trumbull and State of Ohio, have invented a new, original, and ornamental Design for a Corner Sink, of which the following is a specification, reference being had to the accompanying drawings forming part thereof.

Figure 1 is a perspective view of a corner sink showing my new design;

Fig. 2 is a plan view thereof; and

Fig. 3 is a side elevation thereof.

I claim:

The ornamental design for a corner sink, substantially as shown.

JACQUES STANITZ.
